UNITED STATES PATENT OFFICE.

JOHN G. SAUER, OF ROCHESTER, NEW YORK.

AIR-MOISTENING MEANS FOR HOT-AIR-FURNACE FLUES.

Application filed August 20, 1920, Serial No. 404,825. Renewed October 30, 1925.

The present invention relates to air moistening means for furnace flues and more particularly to the type provided with air moistening means, an object thereof being to provide a moistening means which will be effective in operation and not liable to get out of order.

To this and other ends, the invention consists of certain parts and combinations of parts all of which will be hereinafter described, the novel features being pointed out in the appended claims.

In the drawings:—

Fig. 1 is a face view of a vertical flue in which the present invention is embodied;

Fig. 2 is a side view of the flue with parts shown in vertical section;

Fig. 3 is a top view of the flue;

Fig. 4 is a front view of the grille which covers the open upper end of the flue; and

Figs. 5 and 6 are detail views of the cooperating valve members which control the opening upper end of the flue.

Referring more particularly to the drawings, 1 indicates the flue which, in this instance, is rectangular in cross-section and is formed of a number of superimposed sections. The lower section has an intake opening 2 on one face thereof, while the upper section is provided with an outlet opening 3.

This opening is preferably controlled by a valve comprising a fixed plate 4 arranged in front of the opening and a sliding plate 6, both these plates being preferably mounted in a casing 7 supported by brackets 5 and having its front covered by a grille or plate 8. The plates 4 and 6 may be provided with transversely extending slots 9 which, when registering, provide for the outlet of the heated air, and when out of register close the upper end of the flue. The sliding plate 6 preferably has a finger piece 10 rigidly secured thereto and extending through a slot 11 in the fixed or stationary plate 4.

Within the flue, preferably in the upper section thereof, a supply receptacle 12 is mounted, this receptacle having a filling tube 12^a and being arranged above the outlet opening 3, its cross-section preferably being co-extensive with the internal cross-section of the flue. At the bottom of the flue, and within the lower section thereof, is another receptacle 13 which is normally open and has its upper edge below the intake 2, so that the air may pass through the in-

take into the flue. Between the intake and the outlet the flue may be provided with any desired number of open or evaporating receptacles 14, these receptacles preferably being arranged in staggered relation by projecting from opposite side walls of the flue and being spaced from one of the side walls at one end so that a passageway is provided about the evaporating receptacles, the air being caused to flow onto the bottom, then around one end, and then over the top of each evaporating receptacle. The supply receptacle 12 has a discharge 15 in the bottom thereof which connects, by a tube 16, with the evaporating receptacle 14 next below it. Each evaporating receptacle has an overflow connection with the receptacle next below it, this overflow connection being preferably formed by a tube 17 which projects upwardly from the bottom of the receptacle 14 about the opening 18 in said bottom. A tubing 19 also projects about the opening 18 downwardly from the bottom of each evaporating receptacle and about the upper end of the tube 17 in the evaporating receptacle next below it, the tube 19 being of slightly greater diameter than the tube 17 so that a space is provided about the tube 17 through which the overflow may take place. The tube 19 of the lowermost evaporating receptacle 14 depends into the receptacle 13.

With the end in view of preventing the overflow of the receptacle 13, the latter may be provided with a float 20, and this float has a stem 21 projecting upwardly therefrom to the supply receptacle 12, a valve 22 being arranged upon said stem and being adapted, when the receptacle 13 is filled, to close the discharge opening 15 of the supply receptacle 12.

It is apparent that this construction causes the series of evaporating receptacles 13 and 14 to be maintained in filled condition as long as there is any water in the receptacle 12, because the water will flow from the receptacle 12 except when the receptacle 13 is filled, and, when this receptacle 13 is filled, the other receptacles, with the exception of the supply receptacle, must necessarily be filled. It will be noted that the flue may be made of any desirable length by introducing between the inlet section and the outlet section any desired number of intermediate sections with evaporating receptacles therein, it being necessary only to lengthen the

rod 21 to correspond to the length of the flue.

What I claim as my invention and desire to secure by Letters Patent is:

- 5 1. In combination with a vertically arranged flue, having an inlet at its bottom and an outlet at its top, a supply receptacle arranged adjacent the outlet provided with a discharge and a valve controlling said discharge, an open ended receptacle arranged adjacent said inlet, a plurality of open receptacles, one arranged above the other between the inlet and the outlet, the upper one of said plurality of open receptacles receiving liquid from the supply receptacle, overflow connections between the open receptacles, and means in the lower receptacle having connection with the valve of the supply receptacle extending through the overflow connections for controlling the flow of liquid from the supply receptacle to the open receptacle next beneath it.
- 10 2. In combination with a vertically arranged flue having an inlet at its bottom and an outlet at its top; a supply receptacle ar-
- 15 ranged adjacent said outlet, an open receptacle arranged adjacent said inlet, a plurality of open receptacles arranged in staggered relation one above another between the inlet and the outlet, overflow connections between said open receptacles, a float in the lowermost open receptacle, and a valve for controlling the flow of water from the supply receptacle to the uppermost open receptacle.
- 20 3. In combination with a vertically arranged flue having an inlet at its bottom and an outlet at its top; a liquid supply receptacle arranged adjacent the outlet, a plurality of open receptacles arranged below said supply receptacle one above the other, overflow connections between the open receptacles, a valve for controlling the flow from the supply receptacle to the uppermost open receptacle, a valve stem extending through the overflow connections, and a float connected to said valve stem and arranged in the lowermost open receptacle.

JOHN G. SAUER.
